(57) **CLAIM**

The ornamental design for a charging station as shown and described.

DESCRIPTION

FIG. 1 is a front view of a charging station according to the claimed design.

FIG. 2 is a rear view of the charging station.

FIG. 3 is a left side view of the charging station.

FIG. 4 is a right side view of the charging station.

FIG. 5 is a top view of the charging station; and,

FIG. 6 is a bottom view of the charging station.

The dash-dash broken lines in the drawings illustrate portions of the charging station that form no part of the claimed design. The dot-dash broken lines are for the purpose of illustrating the boundaries of the claim and form no part of the claimed design.
